UNITED STATES PATENT OFFICE.

GEORGE ALBERT LYON, OF ALLENHURST, NEW JERSEY.

AUTOMOBILE BUFFER DEVICE.

Application filed May 31, 1923, Serial No. 642,450. Renewed November 20, 1924.

To all whom it may concern:

Be it known that I, GEORGE ALBERT LYON, a citizen of the United States, and resident of Allenhurst, in the county of Monmouth and State of New Jersey, have made a certain new and useful Invention Relating to Automobile Buffer Devices, of which the following is a specification, taken in connection with the accompanying drawing,

10 which forms part of the same.

This invention relates to automobile buffers or bumpers in which one or more of the buffer front members or strips which may be adjustably connected in some cases, may 15 advantageously be formed with diagonally folded ends which may either be disconnected from the adjacent end portions of the front strips or, if desired, may be detachably or permanently connected thereto. 20 This may be conveniently accomplished by forming the buffer front members or strip ends with integral angularly or diagonally folded portions preferably extending rearwardly and forming transversely extending 25 connecting portions which project vertically or transversely sufficiently to be bolted or clamped to a similar folded connector portion of another strip, for instance, which may be arranged in overlapping position in 30 connection therewith. Either of these arrangements gives a neat and desirable finish to the strip ends which may in some cases be formed with two angularly or diagonally folded corners so as to form a diagonally 35 pointed strip end which is especially desirable for buffer fronts of single height or single strip type, thus generally approximating the appearance of a double strip buffer front in which both the strip ends 40 are formed with the angularly folded portions in which the projecting ends are adjacent. While of course it is usually desirable to have the buffer front strips in substantial vertical or transverse alignment 45 with each other at least in the central portions as well as in the other parts of the buffer front, yet in some cases these folded transverse connector portions may be so arranged that the adjacent portions of the 50 strip member are arranged at an angle of ten to twenty degrees more or less from the vertical line joining them. The wide thin spring steel or other strips may also in some cases be either convexly or concavely 55 curved in cross section or oppositely in-

clined in either direction so as to give them a generally convex or concave arrangement so that they have additional stiffness and strength where desired. The buffer strips may be formed with such angularly folded 60 end portions in any desired way as by bending them over suitable forms while highly heated or by suitable die bending operations after which the strips may be hardened and tempered, preferably by being oil quenched while still highly heated after the bending operations. In many cases it is desirable to polish and nickel plate the front face of the buffer front strips which may also advantageously in 65 many cases have this prominent polished nickel plated surface extend around at least the rounded edge of the diagonally folded end portions which may thus be made more prominent than the other or rear surfaces 70 of the buffer strips which may be enameled or otherwise finished in a less prominent manner, if desired.

In the accompanying drawing showing in a somewhat diagrammatic way various 75 illustrative embodiments of this invention:

Fig. 1 is a front view of an illustrative buffer.

Fig. 2 is a top view thereof.

Fig. 3 is an enlarged transverse section 80 taken substantially along the line 3-3 of Fig. 2.

Fig. 4 is a front view of another illustrative buffer.

Fig. 4^a is a similar enlarged transverse 85 section taken substantially along the line 4^a of Fig. 4.

Fig. 5 is a front view of another illustrative buffer.

Figs. 5^a to 5^e are similar enlarged sections 90 of the upper strip taken along the line 5^a of Fig. 5, and

Figs. 6^a to 6^e are corresponding bottom views of the strip.

Fig. 6 is a top view of another illustrative 100 buffer.

Fig. 7 is a partial front view thereof, and

Fig. 8 is a front view of another illustrative buffer front strip.

In the illustrative buffer shown in Figs. 105 1 to 3, the buffer front may be formed of two elements of relatively wide thin spring steel strip which are adjustably connected so as to make the buffer front laterally adjustable to fit automobiles having different 110

width frames. Each of these front elements may comprise two connected front members or strips such as 1, 3 which may be arranged in vertically separated position 5 so as to be in substantial vertical alignment, if desired, with their adjacent edges one to three inches or more apart. The other cooperating front element may comprise the vertically separated connected 10 front strips or members 2, 4 which may be similarly arranged and connected and may have transversely extending strip ends 6, 6 overlapping other front strips which may have their ends 5 arranged somewhat beyond 15 the two connecting or clamping devices 11 of the type shown in greater detail in Fig. 3. Each clamping device may have suitable recesses to accommodate the front strips and may have a threaded hole 15 into 20 which the threaded end of the clamping bolt 17 fits so as to secure these front strips together and hold them securely in connection with the buffer supporting member which may have an inturned connecting end 25 19 behind the front strips and more or less overlapping them, as shown in Figs. 2 and 3. The buffer supporting member or device may be, if desired, of the brace bar type and may comprise a steel strip having 30 the rear supporting or brace bar portion 21 and the curved resilient portions 20, 120 and 22, 123 on its opposite ends beyond the frame ends 24 to which it may be clamped or connected. The inturned connecting 35 ends 19, 23 of this supporting member may thus resiliently support the buffer front strips considerably ahead of the frame ends, if desired.

These buffer front strips or members may 40 advantageously be connected by integral angularly folded connector portions such as 10, 50 which may be arranged behind the front strips and may extend transversely beyond them to a sufficient extent to overlap each other, so as to be securely clamped or connected in any suitable way as by one or more connecting bolts 51 passing through them and having securing nuts such as 52. In this way each of the front elements may 45 be formed of two securely connected strips or members which may be separately formed with these diagonally folded connector portions and then permanently or detachably connected as above described. This, as seen in Fig. 1, forms two angularly 50 or diagonally arranged folded edges 7, 9 at each end of the buffer front, while the central end portion such as 8 is substantially transverse or slightly rounded where a 55 rather rounded or gradual edge bend is formed in these front strips or member which, if desired, may also be rearwardly inclined or bent backward somewhat at 18 as shown in Fig. 2.

Fig. 4 shows another arrangement in

which the buffer front may comprise a front member or strip 25 extending substantially across the buffer front and having angularly or diagonally folded end connector portions detachably or permanently connected 60 so as to connect to this upper front strip the one or more lower front strips such as 26, 28 which may have overlapping end portions 27, 29, if desired. Suitable connecting devices such as 30 may connect these 65 vertically separated front strips or members and securely hold them in vertically aligned position, if desired, while simultaneously connecting them to the connecting portions such as 19 of any suitable buffer supporting 70 member or device. As shown in Fig. 4^a, the upper front strip 25 may be formed with an integral angularly folded connector portion 35 which may extend transversely on the 75 rear of the front strip so as to project down beyond its lower edge and cooperate with a corresponding upwardly extending integral folded connector portion 36 on the end of the adjacent front member 26. These 80 two overlapping connector portions may be 85 permanently or detachably connected in any suitable way as by forming a spot weld 40 therein which securely and permanently connects them so as to form in this case a 90 securely connected buffer front of spring 95 steel strip which may, if desired, be hardened and tempered after it has been bent or formed into the desired shape as by bending over suitable dies.

Fig. 5 shows another illustrative form in 100 which the buffer front members or strips may be separated or disconnected at their ends 39. These front strips or members may, if desired, be substantially parallel at 105 their outer portions such as 37, 38 beyond the connecting devices 30 while their inner or central portions 31, 32 may, if desired, be oppositely bent or curved, as indicated in Fig. 5, so as to form a widened central contact face where this is desired. Each end 110 of these two buffer front strips may, as indicated, be formed with a diagonally folded portion such as 53, 54 which may be bent backward and have its edge 49 forced near or into contact with the rear face of the 115 corresponding strip end, as shown in Figs. 5^a and 6^a, so as to give a finished appearance to the strip end which may be formed with more or less rounded diagonally folded edges 7, 9 as indicated in Fig. 5. When 120 seen from the front this gives the buffer end a desirable and pleasing appearance, especially if the front faces of these front strips are polished and highly finished or nickel plated, together with the somewhat rounded 125 diagonally folded edges 7, 9. Figs. 5^b and 6^b show another illustrative form of diagonally folded strip end 80 where the buffer front strip 33 may have a somewhat more sharply curved diagonal bent edge 81, the 130

somewhat rounded end 82 of the strip being preferably forced into position practically parallel to the adjacent front portion 33 of the strip. Figs. 5^c and 6^c show another illustrative arrangement in which the rounded off strip end 83 is much more gradually bent along a diagonal fold line 84 so as to bring this strip end or edge 83 out into nearly perpendicular position with respect to the adjacent portion 33 of the strip. Figs. 5^d and 6^d show a still more gradual angular or diagonal bend or fold 86, the slightly rounded corner or end 85 of the strip then being bent back along another gradual curve so as to be at its tip nearly parallel to the adjacent portion 33 of this buffer front strip. Figs. 5^e and 6^e show still another desirable illustrative arrangement in which the strip end is also gradually bent or folded along the diagonal or angular line at 87, 88, while the slightly rounded strip end or tip 89 is forced or bent inward to a considerable extent by suitable bending machines which can effectively at a single separation force the strip end into this position.

Figs. 6 and 7 show another illustrative buffer in which the front strips 59, 60 may be substantially parallel with their adjacent edges two to four inches or so apart, if desired, and this buffer front, as in the case of the other types also, may, if desired, be forwardly bent or arched as shown in Fig. 6, although this is not of course necessary in all cases. Each of these front strips or members may be formed with angularly or diagonally bent end connector portions such as 68, 69 shown in Fig. 7 which may be held securely in overlapping position as by the connecting bolt 67 and, if desired, the strip ends 61, 62 adjacent these connector portions may be bent backward somewhat as shown in Fig. 6 which is desirable where this portion of the front strips and their front faces are nickle plated or polished. The buffer supporting member may in this case be a single strip having a rear supporting or brace bar portion 66 to which the forwardly and outwardly curved portions 65 are integrally connected so as to securely support the connecting ends 63, 64 of this supporting member. These connecting ends may overlap the connector portions of the front strips and be bolted or connected thereto as by the connecting bolts 67 shown in Figs. 6 and 7.

In some cases one or more of the buffer front strips may be formed at one or both ends with two angularly or diagonally folded portions as shown in Fig. 8 where a relatively wide front strip 70 of thin spring steel or other material may have its two corners 71, 72 shown in dotted lines in their original position folded backward into the positions 73, 74 behind the strip end so as to form the angular or diagonally

folded edges 77, 79 which gives a good finish to the front strip or other part of the buffer, especially where the front face of this strip and the more or less rounded folded edges are polished and nickle plated, 70 for instance.

This invention has been described in connection with a number of embodiments, forms, proportions, sizes, parts, arrangements, materials, methods of constructions, 75 connection and use, to the details of which disclosure the invention is not of course to be limited, since what is claimed as new and what is desired to be secured by Letters Patent is set forth in the appended claims. 80

1. The automobile buffer front comprising a pair of vertically aligned vertically displaced laterally extending buffer front members formed of wide thin tempered steel strip and each having at each end integral rearwardly extending diagonally folded portions forming the lateral ends of the buffer front and clamping devices secured to both of said vertically displaced members adjacent the buffer ends and 90 adapted to connect them to buffer supporting members.

2. The automobile buffer front comprising a pair of vertically displaced laterally extending buffer front members formed of 95 wide steel strip and each having at each end integral rearwardly extending angularly folded portions forming the lateral ends of the buffer front and clamping devices secured to both of said vertically displaced 100 members.

3. The automobile buffer front comprising a plurality of vertically aligned vertically displaced front buffer members formed of wide steel strip and each having 105 integral rearwardly extending diagonally folded portions adjacent the lateral ends of the buffer front and located substantially entirely between the vertical edges of the end of the connected strip member.

4. The automobile buffer front comprising a plurality of front buffer members formed of wide steel strip and each having integral rearwardly extending angularly folded portions adjacent the lateral ends 115 of the buffer front and located substantially entirely between the transverse edges of the end of the connected strip member.

5. The automobile buffer front comprising a pair of connected vertically displaced laterally extending buffer front members formed of wide steel strip having oppositely bent central portions to form a vertically widened contact face and each having at each end integral rearwardly extending angularly folded portions forming the lateral ends of the buffer front.

6. The automobile buffer front comprising connected vertically displaced laterally extending buffer front members formed of 130

- wide steel strip and each having at each end integral angularly folded portions forming the lateral ends of the buffer front.
7. The automobile buffer front comprising a pair of vertically aligned vertically separated laterally extending buffer front members formed of wide thin steel strip and each having adjacent each of the buffer ends a diagonally folded rearwardly extending portion without direct connection with the adjacent folded end portion of the vertically separated member.
8. The automobile buffer front comprising a pair of vertically separated laterally extending buffer front members formed of wide thin steel strip and each having adjacent each of the buffer ends a diagonally folded portion without direct connection with the adjacent folded end portion of the vertically separated member.
9. The automobile buffer front comprising a plurality of vertically separated laterally extending buffer front members formed of wide thin steel strip and each having adjacent one of the buffer ends an angularly folded rearwardly extending portion without direct connection with the adjacent folded end portion of the vertically separated member.
10. The automobile buffer front comprising a plurality of vertically separated laterally extending buffer front members formed of steel strip and each having adjacent one of the buffer ends an angularly folded portion without direct connection with the adjacent folded end portion of the vertically separated member.
11. The laterally extending automobile buffer front member formed of wide steel strip and having at each end integral rearwardly extending angularly folded portions adjacent the lateral ends of the buffer front.
12. The laterally extending automobile buffer front member formed of wide steel strip and having at each end integral rearwardly extending angularly folded portions.
13. The automobile buffer front member formed of wide thin tempered steel strip and having integral rearwardly extending diagonally folded portions at the lateral ends of the buffer front.
14. The automobile buffer front member formed of wide steel strip and having integral angularly folded portions.
15. The automobile buffer front formed of relatively wide steel strip and comprising connected vertically displaced vertically aligned laterally extending members and integral rearwardly arranged end folds arranged at a substantial angle to each other at the lateral end of the buffer front.
16. The automobile buffer front formed of relatively wide strip and comprising connected vertically displaced laterally extending members and rearwardly arranged end folds arranged at a substantial angle to each other adjacent the lateral end of the buffer front.
17. The automobile buffer front element formed of relatively wide steel strip and having connected transversely displaced transversely aligned laterally extending members and integral rearwardly arranged end folds arranged at a substantial angle to each other at the lateral end of the buffer front element.
18. The automobile buffer front element formed of relatively wide steel strip and having connected transversely displaced members and integral folds arranged at a substantial angle to each other at the end of the buffer front element.
19. The laterally extending buffer front element formed of relatively wide steel strip and having connected horizontally extending transversely separated members and having at each end integral rearwardly extending end folds arranged at a substantial angle to each other.
20. The buffer element formed of relatively wide strip and having connected transversely separated members and having adjacent one end integral obliquely extending folds arranged at a substantial angle to each other.
21. The buffer front element formed of relatively wide steel strip and having connected transversely separated members and having at each end obliquely extending integral folds.
22. The buffer front element formed of relatively wide strip and having connected transversely separated members and having at one end integral rearwardly extending oblique folds.
23. The buffer element formed of relatively wide steel strip and having connected transversely separated members and having integral obliquely extending end folds.
24. The laterally extending automobile buffer front member formed of relatively wide steel strip and having integral obliquely extending folds at one end.
25. The automobile buffer front member formed of relatively wide steel strip and having integral folds at one end arranged substantially at right angles to each other.
26. The automobile buffer member formed of relatively wide strip and having integral rearwardly extending folds adjacent one end arranged at substantially right angles to each other.

GEORGE ALBERT LYON.
